United States Patent Office

Des. 213,442
Patented Mar. 4, 1969

213,442

MODULAR BATHROOM UNIT

Myron J. Ament, Bethel Park, Pa., assignor to The Wallace-Murray Corporation, a corporation of Delaware

Filed Oct. 26, 1967, Ser. No. 9,183

Term of patent 14 years

U.S. Cl. D23—49
Int. Cl. D23—02

Fig. 1

Fig. 2

Fig. 3

Fig. 4

Fig. 5

FIG. 1 is a front elevational view of the modular bathroom unit embodying my new design;

FIG. 2 is a top plan view thereof;

FIG. 3 is a rear elevational view thereof;

FIG. 4 is a side view of the left side thereof; and

FIG. 5 is a side view of the right side thereof.

I claim:

The ornamental design for a modular bathroom unit, as shown.
